UNITED STATES PATENT OFFICE

ARTHUR H. BARROWMAN, OF ATTLEBORO, MASSACHUSETTS, ASSIGNOR TO J. M. FISHER COMPANY, OF ATTLEBORO, MASSACHUSETTS, A CORPORATION OF RHODE ISLAND

BRACELET-EXTENSION DEVICE

Application filed August 11, 1928. Serial No. 298,966.

This invention relates to an extension device of the type employed in connection with bracelet wrist straps and the like to enable the strap to be passed over the hand of the wearer without disconnecting and completely separating any of its parts, and has for its object to permit of an elastic extension to afford comfort to the wearer and at the same time permit of additional enlargement after an extension by unfolding of its sections.

A further object of the invention is the provision of means at each end of the device for securely holding the sections in folded position.

15 The invention further consists in the combination of a unit link bracelet and an extension device, the latter being so formed as to slidably receive one of the bracelet units therein and permit an elastic extension thereof, so that the continuity and flexibility of the bracelet will be substantially the same whether in extended or contracted position.

With these and other objects in view, the invention consists of certain novel features 25 of construction, as will be more fully described, and particularly pointed out in the appended claims.

In the accompanying drawings:

Fig. 1 is a top plan view of the extension 30 in folded position.

Fig. 2 is a top plan view of the extension in unfolded position.

Fig. 3 is a central sectional view on line 35 3-3 of Fig. 2.

Fig. 4 is a perspective view of the housing or channel-shaped section partially broken away to show the abutment therein.

Fig. 5 is a perspective view of the frame 40 which is slidably mounted in the channel section.

Fig. 6 is an end view showing the fingers on one end section frictionally gripping the sides of the channel section.

In the use of watch straps or bracelets to 45 encircle the wrist, especially those used to secure a watch on the arm, it is desirable to afford some means to enlarge the size of the bracelet or strap so that the same may be passed over the hand of the wearer without 50 detaching and separating any of the parts

thereof, and in order to provide such a construction, I have hingedly connected together a plurality of sections and in one of these sections, I have resiliently mounted a slide so that an elastic action is provided to afford 55 comfort to the wearer and in connection with this slide the housing therefor is of a size to receive one of the unit links of the bracelet so that as the elastic extension takes place the bracelet does not change in appearance or 60 in its flexibility; and the following is a detailed description of the present embodiment of this invention illustrating the preferred means by which these advantageous results 65 may be accomplished:

With reference to the drawings, 10 designates the channel or housing section which is provided with a bottom wall 11 and side walls 12 which slidably receive a frame 13 generally rectangular in shape with an opening 14 centrally disposed therein. An abutment 15 is cut and raised from the stock of the bottom wall 11 and extends into the opening 14 to limit the sliding movement of the frame 13. A spring 14^a encircles the 70 frame 13 and engages the abutment 15 to act between it and the lateral projections 16 on the slide frame 13 to move it inwardly from its free end to which the bracelet is attached. These laterally extending abutments 16 are 75 of a dimension to slidably engage the walls 12 and guide the frame in its movement so as to prevent jamming of the spring against the side walls 12. The frame and spring are retained in the housing section 10 by inwardly extending flanges 19 which extend over the sides of the spring and frame to prevent displacement thereof and also serve to more completely house the unit end link 18 of the bracelet.

An end 17 is formed on this frame 13 which is of any suitable shape such as T-shaped to provide a means for connecting a unit link 18 of the bracelet thereto and by means of which the end link 18 is drawn into the 85 housing section 11.

The permitted elastic extension of the frame is sufficient to expose the unit link which is housed therein and as the housed end link 18 would carry the same ornamen- 90 95 100

tation as the remaining link with which it is assembled, the same continuity of appearance would be maintained whether the device were elastically extended or contracted.

5 The bottom wall 11 of the channel section 10 is slotted as at 20 and the intermediate section 21 has an end portion 22 extending thru the slot 20 and rolled about the cross bar 23 formed by this slot to hing- 10 edly connect the intermediate section 21 thereto.

The end section 24 is of an ornamental configuration and has resilient backwardly or downwardly extending fingers 25 ar- 15 ranged in pairs at each end thereof to serve as a means for connecting both ends of the section 24 to both ends of the section 10 when the sections are folded together by resiliently frictionally engaging the side walls 20 12 of the section, as clearly illustrated in Fig. 6. One pair of arms is provided with an opening 26 to receive the laterally ex- 25 tendsing trunnions 27 of the intermediate plate 21 to hingedly connect the same thereto, while the other pair of fingers is pro- vided with openings 27 and receive a suitable connection 28 to pivotally secure an end of the bracelet to the end section 24.

The section 24 in addition to being of an 30 ornamental shape may be pierced as at 30, or otherwise ornamented to conform to the general theme of ornamentation present on the remaining links of the bracelet and in instances where the ornamentation is formed 35 by piercing, it is of advantage to have the intermediate link of substantially the same outline as the ornamental end link 24 so that the piercings will be completely backed and give the same appearance to the top of 40 the device throughout its entire extent.

The intermediate section is of sheet metal construction and bent as illustrated in Fig. 3, so that the greater portion of said section is offset from the channel shaped section so 45 that while hinged to the bottom wall of the channel section 10, it will also overlie the side walls 12 and their inturned flanges 19 of this section and snugly fit against the top surface of the section 24 to give a uniform 50 appearance to any piercings which the top wall may have and to take up the minimum amount of space as to the thickness in the construction.

The foregoing description is directed 55 solely towards the construction illustrated, but I desire it to be understood that I reserve the privilege of resorting to all the mechanical changes to which the device is suscep- 60 tible, the invention being defined and limit- ed only by the terms of the appended claims.

I claim:

1. An extension device comprising end sections and an intermediate section hinged at each end to said end sections to permit 65 folding one over the other, means for secur-

ing one end of a bracelet to one of said end sections, and means for securing the other end of the bracelet to another of the end sections, each end of one of said end sections being provided with a pair of fingers to re- 70 siliently grip the sides of each correspond- ing end of the other end section to hold the sections in folded position, the fingers pro- vided adjacent the hinged end having a portion positioned to engage the other end sec- 75 tion between the hinge connection and the fingers provided at the opposite end.

2. An extension device comprising end sections and an intermediate section hinged at each end to said end sections to permit folding one over the other, one of said end sections being generally channel shape, means for securing one end of the bracelet thereto, another of said end sections being provided with a pair of fingers at each of its ends to re- 80 siliently grip the side walls of the channel section at its opposite ends to hold the sections in folded position, and means for securing another end of the bracelet thereto, the fingers provided adjacent the hinged end 85 having a portion positioned to engage the other end section between the hinge connection and the fingers provided at the opposite end.

3. An extension device comprising a plu- 90 rality of sections hinged together end to end to fold one over the other, one of the end sections being generally channel shape, means for securing one end of the bracelet thereto, the other end section being provided with 100 a pair of fingers at each of its ends to extend over the walls of the channel section and hold the same in folded position, and means for securing another end of the bracelet thereto, one pair of fingers serving as a point of 105 hinging connection for the section to the ad- jacent section.

4. An extension device comprising a plu- 110 rality of sections hinged together end to end to fold one over the other, one of the end sections being generally channel shape in cross section, a frame having an opening therein and movable between the side walls of said channel section, means for attaching one end of the bracelet thereto, an abutment carried 115 by said channel section extending into said opening, guiding means on said frame, a spring acting between the abutment and the guiding means to permit elastic enlargement of the bracelet, inwardly-extending flanges 120 on each of the side walls of the channel section to retain the frame and spring therein, and means to attach another end of the bracelet to the other end section.

5. An extension device comprising a plu- 125 rality of sections hinged together end to end to fold one over the other, one of the end sections being generally channel shape in cross section, a generally rectangular frame hav- 130 ing an open center slidably mounted between

- the side walls of said channel section, an integral extension on said frame of a shape to provide means of attachment of one end of a bracelet, an integral abutment cut and raised from the stock of the channel section and extending into the open center of the frame to limit its sliding movement, a spring encircling said frame and engaging the same and said abutment to permit elastic enlargement of the bracelet, inwardly extending flanges on each of the side walls of the channel section to retain the frame and spring therein, and means to attach another end of the bracelet to the other end section.
6. An extension device comprising end sections hingedly connected together by an intermediate section, means for connecting ends of a bracelet to said end sections, one end section being generally channel shape 20 in cross-section and having bottom and side walls, said intermediate section being hinged to said bottom wall and formed of sheet stock with its greater portion offset with respect to the plane of the bottom wall of the 25 channel section to overlie the edges of the side walls of said channel section.
7. An extension device comprising an end section of ornamental shape, means for connecting an end of a bracelet thereto, another 30 end section being channel shape, and housing means to elastically connect another end of the bracelet therein, an intermediate sheet metal section hinged to the bottom wall of said channel section with its greater portion 35 offset with respect to the plane of the bottom wall of the channel section and of a width to overlie the side walls thereof, said intermediate section being hinged to said ornamental end section and of generally the shape 40 thereof.

In testimony whereof I affix my signature.
ARTHUR H. BARROWMAN.
